UNITED STATES PATENT OFFICE.

FRANK WINTHROP DAVENPORT, OF PROVIDENCE, RHODE ISLAND.

DESIGN FOR A MIRROR-FRAME.

48,152.

Specification for Design.

Patented Nov. 16, 1915.

Application filed August 28, 1915. Serial No. 47,873. Term of patent 3½ years.

To all whom it may concern:

Be it known that I, FRANK WINTHROP DAVENPORT, a citizen of the United States, residing at Providence, in the county of Providence and State of Rhode Island, have invented a new, original, and ornamental Design for a Mirror-Frame, of which the following is a specification, reference being had to the accompanying drawing, forming part thereof, in which—

Figure 1 is a front elevation of a mirror frame illustrating my new design, and Fig. 2 is a side elevation.

I claim:

The ornamental design for a mirror frame as shown.

FRANK WINTHROP DAVENPORT.
